UNITED STATES PATENT OFFICE.

WILLIAM MARION SHELTON, CHARLES BURNHAM MANNING, AND ENOS RALPH CHENEY, OF GYPSUM, KANSAS.

MAIL-BOX-DELIVERY DEVICE.

No. 806,505.

Specification of Letters Patent.

Patented Dec. 5, 1905.

Application filed August 24, 1905. Serial No. 275,610.

To all whom it may concern:

Be it known that we, WILLIAM MARION SHELTON, CHARLES BURNHAM MANNING, and ENOS RALPH CHENEY, citizens of the United States, and residents of Gypsum, in the county of Saline and State of Kansas, have invented a new and Improved Mail-Box-Delivery Device, of which the following is a full, clear, and exact description.

10 The purpose of the invention is to provide a mail-box-delivery device especially adapted to convey mail-boxes to and from a dwelling to the road over which the letter-carrier or messenger on a rural-delivery route passes, enabling persons remote from the road to conveniently and with slight exposure place the letter-box in position to receive mail from and to place mail within reach of the carrier or messenger, the device being entirely under 15 control of the owner of the box, who can draw the box to its starting-point at any time.

20 A further purpose of the invention is to provide a device of the character described which will be economic, effective, simple and durable, and which may be erected over fields without offering any undue impediment to the working of the field and absolutely no impediment to the working of the device.

25 Another purpose of the invention is to so construct the device that the letter-carrier or messenger can gain as convenient access to the contents of the box as if the box were attached to the customary stationary support, and, further, to so construct the device 30 that it is adapted to carry boxes open at the end, top, or sides.

35 The invention consists in the novel construction and combination of the several parts, as will be hereinafter fully set forth, and pointed out in the claims.

40 Reference is to be had to the accompanying drawings, forming a part of this specification, in which similar characters of reference indicate corresponding parts in all the figures.

45 Figure 1 is a perspective view of the improved device. Fig. 2 is a vertical section taken intermediate of the ends of the device. Fig. 3 is a perspective view of the simple form of carrier for a box open at an end, and

50 Fig. 4 is a perspective view of a carrier for the box open at the top and at a side.

A and A' represent two parallel end posts located at the point from which the mail-box is to be sent, and B and B' represent parallel

end posts located at the point at the side of 55 the road at which collection and delivery are to be made. The two sets of end posts A and A' and B and B' face each other, but incline in opposite directions in order to properly stretch a stationary trolley-wire 10, as 60 said wire 10 is secured in any suitable manner between said posts, the attachment being ordinarily made to cross-bars 11 at the upper portions of said posts; but said attachment may be made in any approved manner. The 65 end posts are firmly held in their inclined positions by means of brace-rods 12, attached to the posts and anchored in the ground, and said brace-rods are provided with turnbuckles 13 in order that any slack may be conveniently taken up.

In addition to the inclined end posts A and A' and B and B' intermediate posts 14 are employed in any desired number, and at the upper portion of each intermediate post 14 a 75 horizontal bracket 15 is secured, having an upwardly - extending member 15^a, which members 15^a serve as supports for the trolley-wire 10 intermediate of its ends, as the intermediate posts 14 are set at one side of a 80 line drawn longitudinally through the central portion of the spaces between the sets of end posts A and A' and B and B'. It may be here remarked that the said space between the end posts of a set are sufficiently wide to 85 permit the ready passage of a letter-box C as far as may be required.

A small peripherally-grooved pulley 16 is mounted to revolve between the outer end posts B and B', and a larger similarly-grooved pulley 17 is mounted to turn between the inner ends of the posts A and A', and the shaft 17^a of the larger wheel or pulley 17 is provided with an attached crank-handle 18. The grooved portion of the two 90 wheels 16 and 17 may be roughened, if desired. The wheels 16 and 17 support and drive an endless conveyer-cable 19, which is preferably in the form of a wire of suitable gage, and said cable is guided between the 100 driving-wheels 16 and 17 by being passed in engagement with upper and lower guide-pulleys 20 and 21, as is shown in Figs. 1 and 2. The said upper and lower pulleys are in vertical alinement, and the upper pulleys 20 are 105 mounted in pockets 22, having an opening 23 in the top, and said pockets extend down from the inner ends of downwardly-inclined

bracket-arms 24, secured to the intermediate posts 14, being below and carried in the same direction as the upper brackets 15. At the outer sides of the openings 23 in the pockets 22 an upwardly and outwardly extending guide-arm 25 is formed, which guide-arms, together with the bracket-arms 24, serve to direct the upper stretch of the conveyer-cable 19 to the openings 23 in the pockets 22 10 when the said cable is drawn from the pockets and subsequently left free to return, as happens at periods in the operation of the device, as will be hereinafter explained. The lower stretch of the conveyer-cable 19 passes 15 over the lower guide-pulleys 21, and these latter pulleys 21 are mounted in pockets 26, located at the free ends of bracket-arms 27, secured to the intermediate posts 14 below the bracket-arms 24 and having the same in- 20 clination.

The carrier D for the letter-box C is shown in Fig. 3 in its simple form, being adapted for use in connection with a letter-box which opens at one of its ends, as illustrated in Fig. 25 1, and the form of the carrier shown in Fig. 4 is that adapted for use in connection with a box which opens at a side or at the top. Primarily the carrier D consists of two parallel straps 28 and 28^a, made of pliable metal and 30 having apertures 29 at their end portions, and said straps are held properly spaced by a plate 30, secured to their upper faces at their central portions. A sheave 31 is secured centrally and transversely to the spacing-plate 30, said sheave having an opening 32 in one side, the side adapted to face the intermediate post 14, and in said sheave preferably two grooved pulleys 33 are mounted, adapted to travel upon the trolley-wire 10. 35 When a carrier D thus constructed is to be applied to a box C having a door at its end, the connecting or spacing plate 30 is made to bear centrally and transversely upon the upper face of the box C, and the straps 28 and 28^a are carried down at the sides of the box 40 and along the bottom, as is shown in Fig. 2, until they come together, whereupon they are made to clamp the upper stretch of the conveyer-cable 19 between them and are 45 locked together beneath the said stretch of the cable by bolts passed through their apertures 29.

Where the attachment of the carrier to the conveyer-cable is made, the upper stretch of the cable 19 is drawn sufficiently upward to 55 keep the cable at said point out of the pockets 22 as the carrier passes the pockets, thereby preventing the lower portion of the carrier engaging the pulleys 20; but as soon as 60 the carrier passes a pocket 22 the upper stretch of the cable 19 drops at once of its own account to a reengagement with the pulley 20, guided thereto by either the guide-arm 25 or the bracket-arm 24, belonging to 65 the pulley.

Under the construction of the carrier shown in Fig. 4 the upper portion thereof is identical with the construction shown in Fig. 3; but in addition parallel wires D' are bent upon themselves to form lower horizontal 70 members 34 and upwardly-extending end members 35, which are threaded at their upper portions. The upwardly-extending members 35 of the body portion of the carrier are connected by straps 36 or their 75 equivalents, and the upper threaded portions of the vertical members 35 are carried through the most convenient apertures 29 in the upper straps 28 and 28^a and are provided with nuts 37, so that the body of the carrier 80 may be made to properly clamp and hold boxes of different sizes. It is evident that when a letter-box is secured in the form of the carrier shown in Fig. 4 the door or slide at the side may be readily opened; but 85 should the door or slide be at the top the members 35 are made sufficiently long to permit the upper section to be raised a requisite distance. Under the form of construction of carrier shown in Fig. 4 the cable 19 is attached in any approved manner to the bottom portion of the box. In the form shown in Figs. 1 and 3 the end portions of the cable are those portions which are secured to the carrier, so that the end portions of the 90 abutting ends of the cable are never brought in engagement with the pulleys, and therefore are not liable to be frayed or broken where they are connected.

In operation, the mail-box being adjacent 100 to the inner large pulley or wheel 17, said box is charged with letters and the shaft 17^a is turned in a direction to cause the endless cable 19 to carry the letter-box through the medium of its carrier to the rear end of the 105 device, and when such point is reached the box remains stationary until the letters have been collected by the messenger or collector and the mail-matter to be delivered to the proprietor of the box has been placed therein. 110 Then the shaft 17^a is turned in the opposite direction and the carrier and its box are brought to their starting-point.

It is evident that by means of the devices above described communication can be conveniently established between a residence far from the road side and that the device is not only applicable for the transportation of a letter-box, but also for the transportation of boxes or receptacles adapted to 120 receive groceries, merchandise, and the like.

Having thus described our invention, we claim as new and desire to secure by Letters Patent—

1. A mail-delivery device, consisting of a 125 trolley-wire, a support for the same, an endless cable, means for moving the said cable, a carrier traveling on the trolley-wire and connected with the cable, and means whereby the carrier may be clamped upon a box. 130

2. In a device for delivering mail, a trolley-wire, supports for the ends of the trolley-wire, pulleys mounted to turn in the said supports, an endless cable passed over the said pulleys, intermediate standards located between the end supports for the cable, brackets extending from the said intermediate supports, sundry of the brackets being adapted to support the trolley-wire, other of the brackets having friction-rollers engaging with the said endless cable, a carrier mounted to travel on the trolley-wire, which carrier is secured to the upper stretch of the said cable, and a box located within the carrier.
- 15 3. In a device for delivering mail and like matter, a trolley-wire, supports for the ends of the trolley-wire, standards intermediate of the said supports, the said standards being provided with upper horizontal brackets having sustaining members for the trolley-wire, lower horizontal bracket-arms extend-

ing from said intermediate standards, having pockets formed at their outer ends, the upper pockets being open, guide-pulleys located in the said pockets, wheels mounted to revolve in the end supports, an endless cable passed over said wheels and into engagement with the said friction-pulleys, and a carrier mounted to travel on the trolley-wire, said carrier being adapted to the upper stretch of said cable, elevating said cable at its point of connection therewith, said carrier being adapted to receive and hold a letter-box, as described.

In testimony whereof we have signed our names to this specification in the presence of 35 two subscribing witnesses.

WILLIAM MARION SHELTON.

CHARLES BURNHAM MANNING.

ENOS RALPH CHENEY.
